UNITED STATES PATENT OFFICE.

WILLIAM B. RUSH, OF DECATUR, ILLINOIS, ASSIGNOR TO CHAMBERS,
BERING QUINLAN COMPANY, OF SAME PLACE.

CORN-PLANTER CHECK-ROWER.

SPECIFICATION forming part of Letters Patent No. 298,895, dated May 20, 1884.

Application filed October 5, 1883. (No model.)

To all whom it may concern:

Be it known that I, WILLIAM B. RUSH, a citizen of the United States, residing at Decatur, in the county of Macon and State of Illinois, have invented certain new and useful Improvements in Corn-Planter Check-Rowers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 is a top plan of a check-rower embodying my invention. Fig. 2 is an enlarged top plan of portions of the device. Fig. 3 is a top plan of same parts shown at Fig. 2, but in different relative positions from that shown 20 at said figure. Fig. 4 is a top plan of the auxiliary lever G. Fig. 5 is a perspective of the bars or levers A and G.

25 My invention relates to that class of check-row attachments to corn-planters a type of which is shown at Fig. 1, in which a rocking or oscillating bar, A, is connected by suitable means with and transmits motion to the seed-slides, and receives motion from bars B B' on one side of the bar A, as shown in Patent 30 No. 251,830, or on both sides thereof, as shown in Patent No. 258,216, and in which the bars B B' receive motion from a push-bar, C, which is actuated by connection with forked levers D and a stretched tappet-wire, E.

35 My improvement consists in the use of an auxiliary rocking bar or lever, G, arranged intermediate or between the bar A and the link F, or other device for transmitting motion to the seed-slides, and adapted not only to transmit motion from the bar A to the link F, but to act also as a stop to prevent the momentum of the parts carrying the bar A too far when it is swung, and as a lock to prevent any rebound of the bar A or seed-slides, as herein- 40 after described.

45 The bar G is pivoted near its mid-length to the frame-bar H, or a lug, h, projecting laterally from said frame-bar, and has holes f in its outer end, which receive a bolt or pin, f', 50 to connect the link F therewith. The inner

end of the bar G is forked or terminated by two limbs or ends, g g', with a semicircular groove, g", between them. The under side of one end of the bar A is cut away to form a laterally-projecting shoulder, a, on each side of the bar A, and the bar G is located with its forked end beneath this cut-away portion of the bar A, and in such position with reference to the shoulders a that rocking the bar A on its vertical axis a' will bring the shoulders a alternately in contact with the concave confronting sides of the limbs g g', and thereby give an oscillating motion to the seed-slides through the connecting-rod F or other intermediate mechanism. The bar A has also a laterally-projecting shoulder, a", on each side of its axis of oscillation. When the bar A is given a throw in one direction by impact of the forked lever with a tappet on the tappet-wire, (see Fig. 1,) the limb g is brought thereby in contact with one of the shoulders a" and arrests the movement of the bar A, and thus prevents the momentum of the parts carrying it or other parts out of proper positions, and at the same instant the limb g' is brought in contact with a shoulder a, and prevents any movement backward of the bar A from rebounding of it or the seed-slides. When the bar A is given a throw in the opposite direction to that last described, as shown at Fig. 2, the limb g' then acts on a shoulder a", to arrest the movement, and the limb g on a shoulder a, to prevent rebound.

Having thus described my invention, what I claim as new, and desire to secure by Letters Patent, is—

1. In a check-row attachment to corn-planters, in combination with the oscillating lever A, having shoulders a a", the auxiliary lever G, having limbs g g', adapted to receive motion alternately from the shoulders a, and to act alternately on the shoulders a" as stops, and to transmit motion through suitable mechanism to the planter seed-slides, substantially as and for the purpose specified.

2. In combination with the rocking lever A, which receives motion indirectly from the forked levers D, and has lateral shoulders a", the lever G, arranged between the lever A and mechanism connected with the planter seed-

95

100

slides, and provided with limbs $g g'$, adapted to receive motion from the lever A, and to act alternately on the shoulders a'' as stops, substantially as and for the purpose specified.

5 3. In combination with the tappet-wire E, forked lever D, push-bars C and B B', and rocking lever A, the auxiliary lever G, adapted to receive motion from the lever A, and its arms $g g'$, to act alternately on the shoulders a'' as stops, substantially as and for the purpose specified.

4. In combination with the forked lever D, push-bars C and B B', and rocking lever A, having shoulders a'' , the auxiliary lever G, having limbs $g g'$, adapted to coact with the

shoulders a'' , substantially as and for the purpose specified.

5. In combination with the push-bars C and B B' and rocking lever A, the auxiliary lever G, provided with stops, and adapted to receive motion from and to the motion of the lever A, and to impart movement to the planter seed-slides, substantially as and for the purpose specified. 20

In testimony whereof I affix my signature in presence of two witnesses.

WILLIAM B. RUSH.
